UNITED STATES PATENT OFFICE.

EDGAR A. CUSTER, OF PHILADELPHIA, PENNSYLVANIA, ASSIGNOR TO THE CUSTER SANDLESS CASTING COMPANY, OF WILMINGTON, DELAWARE, A CORPORATION OF DELAWARE.

METAL PRODUCT FROM CAST-IRON.

No. 927,496.

Specification of Letters Patent. Patented July 13, 1909.

Application filed February 26, 1909. Serial No. 480,251.

To all whom it may concern:

Be it known that I, EDGAR A. CUSTER, a citizen of the United States, residing at the city of Philadelphia, in the county of Philadelphia and State of Pennsylvania, have invented certain new and useful Improvements in Metal Products from Cast-Iron, of which the following is a specification.

My invention has relation to producing from cast iron a metal product adapted to take a temper.

My invention, basically considered, consists of a metal product having the chemical constituency of cast iron and the physical property of taking a temper.

The nature and general scope of my invention will be more fully understood from the following description taken in connection with the accompanying drawing forming part hereof, in which—

Figure 1, is a view of a plant susceptible, instrumentally, of being employed to produce the metal product embodying the features of my said invention; and Fig. 2, is a view in perspective, illustratively, of the metal product adapted to take a temper, derived from cast iron according to my invention.

Referring to the drawing 1, represents a cupola-furnace provided with a pouring spout *a*, and ladle *a'*, the ladle being placed in proximity to a permanent sectional metal mold 2, consisting of a cope *b*, and drag *b'*, having pour-holes *b''*, located about the meeting edge of the two sections of the mold 2, and having internal channelways, not shown, directly leading to a central cavity *b''*, of any required shape or form, according to the shape or form of the homogeneous solid structure to be cast in the mold. The molten metal from the cupola-furnace 1, passes by the pouring-spout *a*, into the ladle *a'*, and then into the mold 2, in which it swiftly chills

to the point of setting, covering as to time, but a few moments. The mold is preferably then automatically opened, by parting the cope *b*, from the drag *b'*, if as shown, it is a horizontal mold; or if a vertical mold, separating one part or section from the other, so that the cast structure, set in the mold can immediately be removed. It can then be quenched in a tank of water 3, while still hot and give a resultant product having the chemical constituency of cast iron and some of the physical properties of steel. It has also been demonstrated that the metal product, as hereinbefore described, may be subjected to magnetic influences and retain sufficient magnetism to become, due to the character of the metal, a permanent magnet.

Having thus described the nature and objects of my invention, what I claim as new and desire to secure by Letters Patent is:—

1. As a new article of manufacture, a metal product having the constituency of cast iron and property of taking a temper.
2. As a new article of manufacture, a homogeneous metal product having the constituency of cast iron and property of taking a temper.
3. As a new article of manufacture, a homogeneous metal product having the chemical constituency of cast iron and physical property of taking a temper.

4. As a new article of manufacture, a metal product having the constituency of cast iron and property of becoming, by the character thereof, a permanent magnet.

In witness whereof, I have hereunto set my signature in the presence of two subscribing witnesses.

EDGAR A. CUSTER.
